UNITED STATES PATENT OFFICE.

GEORGE WILKINSON, OF PROVIDENCE, RHODE ISLAND, ASSIGNOR TO THE HOLMES & EDWARDS SILVER COMPANY, OF BRIDGEPORT, CONNECTICUT.

DESIGN FOR A SPOON.

SPECIFICATION forming part of Design No. 20,901, dated June 30, 1891.

Application filed May 25, 1891. Serial No. 394,063. Term of patent 14 years.

To all whom it may concern:

Be it known that I, GEORGE WILKINSON, a citizen of the United States, residing at Providence, in the county of Providence and State of Rhode Island, have invented and produced a new and original Design for Handles for Orange-Spoons; and I do declare the following to be a full, clear, and exact description of the same, reference being had to the accompanying illustration, forming a part thereof.

The figure is a representation of my novel design in elevation.

The leading feature of the design consists in the representation in outline and configuration of a branch or twig of an orange-tree, said branch or twig bearing upon it leaves of

the orange-tree, buds, a blossom, and the fruit of said tree.

a denotes the representation in outline and configuration of a branch or twig of an orange-tree, *b* the leaves, *c* the buds, *d* the flower, and *e* the fruit, of the orange-tree.

What I claim is—

The design for the handle of an orange-spoon, substantially as herein shown and described.

In testimony whereof I affix my signature in presence of two witnesses.

GEORGE WILKINSON.

Witnesses:

JOHN F. C. LAWTON,
THEODORE A. BARTON.
